"Local Components", FIG. 3.14 Special heavy wall fittings.

Primary Examiner—James R. Largen

Attorney, Agent, or Firm—Pravel, Gambrell, Hewitt, Kirk & Kimball

[57] CLAIM

The ornamental design for a welding outlet, substantially as shown and described.

DESCRIPTION

FIG. 1 is an elevational view taken from one side of a welding outlet showing my new design; the opposite side being a mirror image of the side shown;

FIG. 2 is a top view thereof;

FIG. 3 is a bottom view thereof;

FIG. 4 is an elevational view taken from one end thereof; and

FIG. 5 is an elevational view taken from the end opposite that shown in FIG. 4.
